UNITED STATES PATENT OFFICE.

Before the Commissioner of Patents,
Washington, D. C.,
JOSEPH FRITSCHE, of PUENTE, CALIFORNIA.

BEAN-VINE CUTTER.

1,252,337.

Specification of Letters Patent.

Patented Jan. 1, 1918.

Application filed July 23, 1917. Serial No. 182,240.

To all whom it may concern:

Be it known that I, JOSEPH FRITSCHE, a citizen of the United States, residing at Puente, in the county of Los Angeles and State of California, have invented new and useful Improvements in Bean-Vine Cutters, of which the following is a specification.

My invention relates to harvesting machinery and especially to bean vine cutters.

10 My object is to make a bean vine cutter having two cutting blades swinging to and from each other, and provide means for imparting a universal movement to each blade from a single handle for each blade.

15 A further object of my invention is to provide a bean vine cutter capable of wide manipulation as required for use upon rough ground.

Another object of my invention is to provide a bean vine cutter which is simple, durable, and easily operated, and not liable to get out of order.

Other objects will appear hereinafter.

The drawings illustrate the invention.

25 Figure 1 is a perspective of a bean vine cutter embodying the principles of my invention.

Fig. 2 is a fragmentary inside sectional elevation of one of the handles and its connections.

The runners 1 and 2 are cut from boards such as two by four or two by six scantling, and each runner has a shoe 3 of strap iron turned up at its forward end. Metal straps 4, 5, 6 and 7 are secured vertically at their lower ends to the inner faces of the runners and said straps are inclined inwardly from the upper edges of the runners. Metal straps 8, 9, 10 and 11 are secured against 35 the outer faces of the runners in transverse alinement with the inner straps, said straps being held by bolts or rivets 12 passing through the outside straps and through the runners and then through the inside straps.

40 The upper ends of the straps 4, 5, 6 and 7, and the straps 8, 9, 10 and 11 are bent horizontally inwardly and in alinement, and the beams 13 and 14 are mounted upon these bent upper ends and secured by bolts or rivets 15. Boards 16 and 17 are mounted longitudinally upon the beams 13 and 14, one on each side of the center, to form a platform. The tongue 18 is mounted on top 45 of the rear beam 13 and under the forward beam 14 and extends forwardly beyond the ends of the runners and carries a

clevis 19 for the reception of a swing-tree or double-tree, and the tongue also extends backwardly beyond the rear beam 13 and carries a handle 20 upon its extreme 60 rear end. The frame thus produced is in effect a sled, the runners being spaced a proper distance apart to straddle a row of beans. A longitudinally extending bearing 21 is formed at the lower end of the strap 65 4 and a similar bearing (not shown) is formed at the lower end of the strap 6. A pintle 22 is rotatably mounted in the bearing 21 and has a bifurcated head 23. The cutter blade 24 is mounted in the bifurcation of the head 23 and held in place by 70 the pivot 25 so that the blade may swing to and from the runner 1 in a horizontal plane and so that it may rotate on the pintle 22. The edge 26 of the blade is toward 75 the center of the frame. A tooth 27 extends downwardly from near the longitudinal center of the blade, said tooth being flat in a longitudinal direction so that it will cut into the ground as the machine moves forwardly. A bearing bracket 28 is fixed to the inner face of the runner 1 a short distance behind the beam 14 and extends inwardly. A lever 29 is pivotally connected to the bracket 28 by a pin 30 near its lower 80 end so that the lever may swing in a transverse direction. A toothed sector 31 is fixed upon or formed integral with the upper end of the lever 29 and extends in a longitudinal direction. A clevis link 32 is 85 hinged to the lower end of the lever 29 by a pin 33 extending in a longitudinal direction and is hinged to the blade 24 by a pin 34 extending in a vertical direction so that when the lever 29 is vibrated transversely the 90 free rear end of the blade 24 is swung to or from the runner 1. The second hand-lever 35 is connected to the lever 29 by an angle bracket 36 carrying a pivot pin 37, said pin extending transversely so that the lever 100 may swing longitudinally. An arm 38 extends from the lower end of the lever 35 rearwardly, and an off-set link 39 connects the rear end of this arm 38 to an angle link 40 by a pivot pin, and the angle link 40 105 is connected to a bracket 41, extending upwardly from the blade 24, by a pivot 42, so that a transverse and a longitudinal joint is produced between the link 39 and the blade 24. The handle 43 is formed upon the 110 upper end of the lever 35 and a pawl 44 carried by the lever 35 engages the teeth 45

of the sector 31, to prevent the blade 24 from swinging downwardly when the pawl is adjusted. A link 46 connects the pawl 44 to the grip 47 pivotally mounted upon 5 the handle 43, so that when the handle 43 is grasped and the grip 47 pressed toward the handle, the lever 35 may be swung forwardly or backwardly to raise or lower the blade 24. A keeper 48 is fixed upon the 10 outer face of the runner 1 and extends upwardly, and a toothed-rack 49 is pivoted to the lever 29 and slidingly mounted transversely and horizontally through the keeper 48, there being teeth upon the lower edge 15 of the rack 49 to grip the keeper and hold the upper end of the lever 29 from swinging inwardly. A link 50 connects the toothed-rack 49 to the grip 51 pivotally mounted upon the opposite side of the handle 43 from 20 the grip 47, so that when the handle 43 is grasped and the grip 51 pressed toward the handle the rack 49 is raised out of engagement with the keeper 48 and the lever 29 may be swung transversely upon the pivot 25 30 to move the blade 24 toward or from the runner 1. In a similar manner the blade 52 is mounted inside of the runner 2 and manipulated by the handle 53.

The blades 24 and 52 normally extend 30 from the runners 1 and 2 backwardly and inwardly, and, as before suggested, the rear ends may be swung to and from each other by manipulating the handles 43 and 53. The edge 54 of the blade 52 is toward the edge 35 26 of the blade 24, and by manipulating the handles these edges may be turned upwardly or downwardly, these movements being provided for by the pintles 22.

The details of construction may be varied in many ways without departing from the 40 spirit of my invention as set up in the following claims.

I claim:

1. A bean vine cutter comprising runners rigidly connected together, a pivoted cutter blade extending inwardly and backwardly from one of the runners, a handle mounted to swing transversely and longitudinally, and connections between the handle and the cutter blade. 50

2. A bean vine cutter comprising runners rigidly connected together, cutter blades rotatably and pivotally connected to the runners and extending inwardly and backwardly, handles pivotally mounted upon 55 the runners for longitudinal and transverse movement, and means for transmitting said movements to the cutter blades.

3. A bean vine cutter comprising runners rigidly connected together, cutter blades 60 pivotally and rotatably connected to the runners and extending inwardly and backwardly, levers pivotally mounted inside the runners to swing transversely, links connecting the lower ends of the levers to the cutter blades, second levers pivoted to the first levers to swing longitudinally, arms extending backwardly from the lower ends of the second levers, double jointed links connecting the arms to the cutter blades, handles 70 for the second levers, and means for holding the handles in adjusted positions.

In testimony whereof I have signed my name to this specification.

JOSEPH FRITSCHE.

Copies of this patent may be obtained for five cents each, by addressing the "Commissioner of Patents, Washington, D. C."
